UNITED STATES PATENT OFFICE

EMILE S. GUIGNON, JR., OF KANSAS CITY, MISSOURI, ASSIGNOR TO POINT-O-PURCHASE COMPANY, OF KANSAS CITY, MISSOURI, A CORPORATION OF MISSOURI

SIGN

Application filed January 3, 1933. Serial No. 649,847.

This invention relates to combined display sign and illuminator particularly useful in store windows or in any place where it is desired to illuminate a given area and, at the same time, advertise through an illuminated sign, any particular commodity.

The primary object of this invention is to provide a unique and novel sign structure, wherein are built adjustable lamps that may be moved toward and from an opening formed in the sign casing for the purpose of varying the area that is illuminated beneath the sign by light rays passing through the opening in the sign case.

Another object of the invention is the contemplation of means whereby a lamp within a sign casing may be moved for adjustment through paths of travel that are perpendicular to each other, whereby focusing or projecting of light rays might be controlled to suit any condition.

A further aim of the invention is the provision of unique means for carrying out the foregoing objects, and during the course of the following specification one form of a sign structure embodying the broad concepts of the invention will be described. In the accompanying drawing:

Figure 1 is a vertical section through a sign casing embodying this invention.

Fig. 2 is a vertical cross section through the same.

Fig. 3 is a horizontal cross section through the sign, taken on line III—III of Fig. 1, and.

Figs. 4 and 5 are diagrammatical showings of a sign structure embodying this invention, with the lamps thereof positioned at two points of adjustment whereby the area illuminated is changed.

In producing a sign of the character contemplated by the invention. It is desirable to construct a casing to present opposite sides 8 that are formed of transparent or translucent material so that any form of display might be carried thereby and made distinct by the hereinafter described lamps carried within the sign casing. The sign has sides 8 joined by ends 10 and a top 12 is provided so that a completely closed cas-

ing, with the exception of the open bottom, is presented. In other words, an opening 14 is formed through the bottom of the sign casing contemplated by this invention, and in the preferred form, is left entirely unobstructed, not only to permit free passage of light rays therethrough, but to allow reaching into the sign casing so that adjustment of the lamps might take place. This sign casing should have a reflector 16 there- 55 in to direct the rays of light outwardly through sides 8, and since a current of air will be drawn into the casing through opening 14, it is preferred to form ventilating holes 18 and 20 through top and reflectors 60 12 and 16 respectively.

The structure of this aforementioned sign casing is much the same as that described in co-pending application Serial Number 586,510, filed January 14, 1932, and when the 70 adjustable lamps are incorporated in such a sign, a decided step forward in the art seems to have taken place. It is desired to support this combined display sign and illuminator in store show windows at a point 75 substantially on the line of vision, and since the lamps in the sign are utilized to direct rays through translucent sides 8, as well as to flood the floor of the display window with a shadowless, white light, and further since 80 the floor areas of display windows will vary, it has been found desirable to support one or more lamps 22 in the manner shown.

In this instance there is one lamp carried by each end 10 and the novel manner of supporting lamp 22 may be to provide a pair of tracks 24 in the form of inturned flanges that extend substantially the full height of end 10. A resilient, substantially U-shaped bracket 26, having outturned feet 28, is engaged by opposed tracks 24 by causing feet 28 to set beneath the aforementioned inturned flange of each track 24. The frictional engagement set up between bracket 26 and tracks 24 will serve to maintain lamp 95 22 in the desired position. It is obvious that lamp 22 is movable in a rectilinear line toward and from opening 14 and to further allow control of the projected light rays, lamp 22 is also adapted to move in a rec- 100

tilinear line transversely to the aforesaid rectilinear path of travel. This expedient is accomplished by forming bracket 26 with a tubular portion 30 which tele-

5 scopingly receives tubular stem 32 directly integral with socket 34, which carries lamp 22. Wires 36 carry current to lamp 22 and extend through the telescoped cylindrical members 30 and 32. Manifestly, wires 36

10 should be of sufficient length to permit the desired adjustment.

A relatively tight frictional fit between parts 30 and 32 will hold lamp 22 in an adjusted position at any point in its path of travel toward and from the adjacent end 10, and when it is desired to move bracket 26 along track 24, the sides of bracket 26 may be pressed toward each other to relieve their tension outwardly against said tracks.

15 26 A further forcing together of the sides of bracket 26 will permit removal of the entire lamp assembly.

In the drawing a lamp 22 has been shown carried by each end 10, and it is plain that 25 lamps may be carried by either one or both of ends 10.

Having thus described the invention, what is claimed as new and desired to be secured by Letters Patent is:

30 1. An illuminator of the character described comprising a casing having two of its opposed sides formed of translucent material and an opening formed through the bottom intermediate the ends of the casing to permit uninterrupted passage of light rays from within the casing; a lamp adjustably mounted within said casing between said opposed sides and at the end of the casing for movement toward and from said opening; and means carrying the lamp for movement toward and from the ends of said casing.

2. An illuminator of the character described comprising a casing having two of its sides formed of translucent material and an opening formed through the bottom thereof; a bracket slidably mounted inside said casing on the end thereof for movement toward and from the said opening; and a 45 50 lamp slidably carried by said bracket for movement toward and from said end of the casing.

3. An illuminator of the character described comprising a casing having an opening formed through the bottom thereof; a pair of opposed tracks carried by one end of said casing on the inner side thereof; a bracket slidably carried by said tracks; and a lamp carried by the bracket, said bracket 55 60 being resilient so as to frictionally engage the tracks and maintain the same in any position along the length of the tracks.

4. A display sign of the character described comprising a casing having translucent panels forming two opposed sides

thereof, ends connecting said sides and a top joining said ends and sides whereby to form an open-bottomed casing; a pair of tracks carried by each end of said casing interiorly of the latter; a resilient bracket 70 frictionally engaging said tracks whereby to be held in an adjusted position; a lamp carried by the bracket; and telescoping members joining said lamp and bracket to permit movement of the lamp toward and from 75 the end of said casing.

In testimony whereof, I hereunto affix my signature.
